CLOSURE FOR CONTAINERS

George Arlington Moore, Louisville, Ky., assignor
to Humoco Corporation, Louisville, Ky., a corporation of Delaware

Application November 6, 1935, Serial No. 48,483

16 Claims. (Cl. 93—36.5)

This invention relates to closure means for containers, and more particularly to a fiber or paper cap adapted for use with metallic or glass jars, bottles, etc., as well as with containers made of fibrous materials.

One of the objects of the present invention is to provide a novel cap adapted as a closure for glass, metallic and other containers which is much less expensive than metallic or similar caps and which forms a more effective seal than caps heretofore provided for such containers.

Another object of the invention is to provide a novel cap which may be readily removed and replaced by hand and yet one which will adhere to the associated container in such a manner as to provide a substantially hermetic seal.

Still another object is to provide a novel sealing cap which is so constructed that the same may be readily and easily removed from a container, irrespective of the temperature changes and the coefficient of expansion of the material of which the container is constructed.

A further object is to provide novel sealing means for a container which may be readily removed without the use of instrumentalities and may be replaced for resealing as originally packed.

A still further object is to provide a closure for a container which embodies the characteristics and advantages of a rigid closure member but which is sufficiently flexible and resilient to readily conform itself to irregular surfaces and provide a hermetic seal without the application of additional sealing substances or parts.

Another object is to provide a closure for containers which is so constructed as to avoid any possible danger of chipping or breaking a glass container when said closure is applied to or removed from the same.

A further object is to provide a novel laminated cap for a container such as a glass or metallic container which is so constructed as to obviate the necessity for gaskets to secure a tight seal, the cap being so formed as to maintain its original characteristics over a very substantial period of time and during constant use.

The above and other objects and novel features of the invention will more fully appear from the following detailed description when taken in connection with the accompanying drawing. It is to be expressly understood, however, that the drawing is for purposes of illustration only and is not designed as a definition of the limits of the invention, reference being primarily had for this latter purpose to the appended claims.

In the drawing, wherein like reference char-

acters refer to like parts throughout the several views,

Fig. 1 is a half top plan view, with parts broken away, of one form of laminated blank which may be employed in forming the cap of the present invention;

Fig. 2 is a sectional view of the blank, taken on line 2—2 of Fig. 1, the thickness of the laminations being represented on an enlarged scale;

Fig. 3 is a half elevation view in section illustrating the blank after the same has been subjected to the first step in the formation of the cap;

Fig. 4 is a view similar to Fig. 3 illustrating the blank after the completion of the second step of the forming operation;

Fig. 5 is a sectional view of the completed cap; and,

Fig. 6 is a side elevation illustrating the cap in sealing position on a container.

One embodiment of the novel closure member comprehended by this invention is illustrated, by way of example, in the form of a screw cap adapted to threadedly engage and seal a container having cooperating screw threads thereon. Said closure or cap may be formed from a single blank of paper or other fibrous material, but preferably the same is formed from a blank constituted by a plurality of paper and metal foil laminations, the foil laminations constituting, in effect, a core and being employed for the purpose of giving body and metallic characteristics, such as toughness, to the cap and to insure the imperviousness thereof to penetration by air and moisture. The metallic core also operates to anchor the fibrous material of the closure flange against undue expansion after the same has been subjected to the drawing and flowing operations to be hereinafter described. As shown in Fig. 2, a blank 9 which may be employed in making the cap of the present invention is circular and comprises a layer of foil 10 which is sandwiched between and reinforced by layers 11 and 12 of paper or other fibrous material. In order that the elasticity and resiliency of the completed blank shall be somewhat greater than that of foil layer 10 and for the purpose of increasing the tenacity of the bond between said foil and the paper layers, the former is preferably slightly corrugated or embossed or the surface thereof roughened, as illustrated in Fig. 2.

The layers of material constituting blank 9 may be secured to one another in the relation illustrated by means of a suitable adhesive applied to the surfaces of layers 11 and 12 which

engage foil layer 10 and, if desired, an adhesive coating may also be applied to either or both surfaces of the foil layer. The adhesive or glue is preferably applied to the layers constituting blank 9 in the form of a thin dried film 13 adapted to be activated by a suitable solvent, heat, or both. To avoid the presence of excessive moisture between the laminations and to avoid shrinkage and consequent wrinkling of the paper layers when the glue dries after activation by a solvent, the adhesive 13 employed should carry only about 10% to 12% of moisture and should be rendered tacky whenever the moisture content is raised to from 22% to 27%. Animal or dextrine glues and some vegetable adhesives have been found suitable.

In addition to the above, superior results are obtained if an adhesive having a rubber or latex base is employed to thereby insure against any cracking of the dried film thereof between the layers of material when the blank is being deformed in a manner to appear hereafter. The flexibility of the completed cap is also enhanced when such a glue is used. It will be noted that when the coatings of glue 13 are activated by applying a solvent thereto and the paper laminations 11 and 12 are pressed against the foil layer 10 the activated glue flows sufficiently to fill the crevices in the embossed or roughened surface of said foil layer and the pores and crevices of the paper layers thus interlocking the same and minimizing any relative slippage during the formation of the cap.

It may be desirable that the inner surface of the completed cap, i. e., the surface which comes in contact with the contents of the containers, be repellent to moisture. Accordingly, to render layer 11 moisture proof and also to increase the sealing qualities of the cap, the surface of the central portion of said layer is, in the form shown, coated with a protective film 14 of high gloss lacquer which is not affected by moisture or heat at ordinary atmospheric temperatures. One suitable lacquer which has been found to have such characteristics is constituted by about equal percentages of solvents and solids, the former comprising ethyl acetate diluted with alcohol and toluol, while the solids are made up about 30% of low viscosity nitro-cellulose, 10% of a plasticizer, such as a modified cocoanut oil, and 60% of synthetic resins whose chief characteristics are transparency and gloss. A similar coating may also be applied to the outer surface of layer 12, which surface may be printed before the application of the lacquer to thus obviate the necessity of a label.

For a purpose to appear hereafter, the marginal portion 15 of the outer surface of layer 11, which is the inner surface of blank 9, is precoated with a thin dried film 16 of lacquer which possesses adhesive qualities and is capable of activation either by a solvent, heat, or both, but by heat only at temperatures considerably in excess of probable room temperatures, for example, 150° to 160° F. One suitable lacquer which has been found to fulfill the above requirements and accomplish the desired results is composed about 65% of such ester solvents as ethyl acetate, butyl acetate, or the like, and such hydrocarbons as toluol, and 35% of solvents which can be readily activated by solvents as well as heat. The solids content is composed of about 25% of low viscosity nitro-cotton, about 15% of a plasticizer, such as dibutyl phthalate which may have a small 75 amount of vegetable oils added thereto, and 60%

of synthetic resins which preferably contain some gums, such as ester gum. This thermoplastic lacquer film 16 also has moisture-proofing qualities and may, if desired, be applied to the entire surface of layer 11 either with or without the 5 non-thermoplastic lacquer film 14 heretofore described.

The blank thus constituted and coated is subjected to a series of forming steps to make the same into a novel closure member, one form of 10 which is illustrated in Fig. 5. The first step of the forming process consists in a drawing and forming operation whereby an annular inwardly projecting rib or ridge 17 is formed about the central portion of the blank and the marginal portion 15 thereof is drawn into flanged relation with said central portion in accordance with the process described in my Reissue Patent No. 19,504, for Flanged reinforced paper article and process of making same. Rib 17 may be formed by a 20 pair of cooperating male die members acting against the upper and lower surfaces of the blank, one of said dies having an annular raised portion or bead thereon complementary to a groove in the face of the other of said dies. Said bead and groove may be shaped to form a rib of any desired contour, but the same is preferably formed with a plane inner surface 18 of considerable width measured along the radii of the blank. Rib 17 gives strength and radial rigidity to the cap 30 or closure member and also adds to the longitudinal resiliency and flexibility thereof. Surface 18 of the rib is accordingly effective to yieldingly engage and conform itself to the upper edge of a container 19 with which it is adapted for use 35 to thereby form a tight seal.

During the formation of rib 17, the marginal portion 15 of blank 9 is yieldingly held against wrinkling or bending along radial lines and at the same time said blank is drawn into a female 40 die member by the movement of the above mentioned male die members. Margin 15 is thus drawn upwardly to form a smooth annular flange 15a. Preferably a groove 20 having a width comparable to the thickness of blank 9 is provided 45 between rib 17 and flange 15a.

The second step of the forming operation consists in flowing the upper portion of flange 15a, as seen in Fig. 3, inwardly and downwardly until the raw edge of said flange projects into groove 50 20, as illustrated in Fig. 4. The inflowing or folding of margin or flange 15a is preferably carried out by a reciprocating male die member having a curved annular groove in the lower edge thereof adapted to engage the upper edge of said flange 55 while the blank is held by a suitable female die member, substantially as disclosed in my above mentioned reissue patent. It will be noted that the flange thus formed is substantially homogeneous throughout.

In carrying out the third and last forming step, blank 9 in the form shown in Fig. 4 may be supported in a female die and subjected internally to radial pressure by suitable segmental dies having beads thereon adapted to form contours such as helical groove 21 in the inner wall of the flange of the cap, said groove being adapted to cooperate with threads on container 19. Preferably the female die is also provided with a thread-like groove complementary with helical bead on the 70 segmental dies so that when pressure is applied by the latter, groove 21 is formed in the inner surface of flange 15a and a complementary bead 22 is formed on the outer surface thereof. Preferably the segmental dies are so constructed as 75

to apply pressure throughout the inner face of the inflowed portion of flange 15a at the same time that a longitudinal pressure is applied to the folded edge 23 thereof with the result that the 5 raw edge of the inflowed flange portion is forced downwardly and buried in groove 20 intermediate rim 14 and the adjacent side wall of the flange.

The pressure exerted outwardly against flange 10 15a by the segmental dies is resisted by the female die supporting the blank and said latter die may be provided with suitable heating means such as a steam conduit or electric heating coils. Heat 15 from the die is conducted by the material of flange 15a to the thermoplastic adhesive 16 with which the margin 15 of blank 9 is precoated, as pointed out above. The adhesive being thus activated is caused by the exerted pressure to flow into the interstices of the paper layer 11 and substantially weld the folded portions of flange 20 15a together, as illustrated at 24. At the same time, the adhesive between layers 11 and 12 and foil layer 10 is activated, thus setting said foil layer so that the same will resist any expanding 25 tendencies of the fibrous materials which were compressed during the drawing of the flange. This, aided by the fact that there are two metallic layers in the flange, also gives rigidity to said flange without disturbing the flexibility of the 30 head or central portion of the closure.

When the cap formed in the manner set forth above is applied to containers such, for example, as glass container 19, grooves 21 cooperate with threads on the neck of said container to move 35 rim 17 into sealing engagement with the upper edge of said container. The flexibility of the top 40 of the cap permits rim 17 to conform itself to the entire surface of the edge of the container, and this firm and complete engagement, assisted 45 by the non-thermoplastic film of lacquer 14, constitutes a substantially impervious seal, it being unnecessary to employ a gasket such as is required to be used with a rigid or metallic cap 50 to secure a good seal. In addition, the inner diameter of flange 15a of the completed cap (Fig. 5) is substantially the same as or slightly less than the outer diameter of the neck of container 19, and the natural resiliency and flexibility 55 of said flange cause the same to snugly engage and conform itself to said neck, thereby giving material assistance to rim 17 in forming an impervious seal. The elasticity of the cap also gives assurance that the same may be easily removed at all times irrespective of temperature 60 changes and the coefficient of expansion of the material of the container. Also, the coefficient of friction between paper and glass is considerably less than that between a metal cap and a glass container, for example, and seizing or binding 65 between the cap and container, which often results in breakage or chipping of a glass container, is eliminated by the use of the cap here provided.

There is thus provided a novel closure for a 70 container which may be inexpensively and readily manufactured in large quantities and which may be employed for effectively sealing containers made of any kind of material. The novel closure is so constructed that the same may be readily applied to and removed from a container without 75 the use of instruments and without danger of damaging the cap or container. Although only one embodiment of the invention is illustrated and described, it is to be expressly understood that various changes may be made without de-

parting from the spirit and scope of the invention. For example, other well-known securing means may be impressed in the flange of the cap in lieu of the helical thread 21 and blank 9 may be composed of other arrangements of paper and foil laminations or wholly of paper 5 laminations, if desired. Also, thread 21, 22 may be reversed, i. e. with bead 22 projecting inwardly. Various other changes may also be made in the design illustrated, as will now be apparent to those skilled in the art. For a definition of the 10 limits of the invention, reference will be had to the appended claims.

What is claimed is:

1. An article of the class described comprising a laminated circular blank with an annular rib formed centrally thereof and having an annular marginal portion of the blank drawn into flanged relation with the central portion thereof, a part of the flange being folded inwardly and secured to the remainder thereof by an adhesive, 20 and a groove and complementary bead in said flange adapted to cooperate with means on the container.

2. A closure for containers comprising a circular blank, the marginal portion of which is folded 25 into a multi-ply flange, the folds of which are consolidated by a thermoplastic adhesive, and the central portion of said blank having an inwardly extending rib thereon adapted to engage the edge of the container surrounding an opening 30 therein.

3. The process of making a container closure comprising a fibrous material which consists in drawing the marginal portion of a blank into flanged relation with the center thereof and inflowing said marginal portion to form a multi-ply flange, and simultaneously pressing and heating the plies of said flange to activate a thermoplastic adhesive thereon and consolidate said 35 plies. 40

4. The process of making a container closure comprising a fibrous material which consists in drawing the marginal portion of a blank into flanged relation with the center thereof and inflowing said marginal portion to form a multi-ply flange, simultaneously pressing and heating 45 the plies of said flange to activate a thermoplastic adhesive thereon and consolidate said plies, and deforming said flange by the application of pressure to cooperate with means on the container 50 for securing said closure thereto.

5. An article of the class described formed from a blank comprising fibrous materials, said article including a central portion, a multi-ply flange, and a portion constituting a groove and joining 55 said flange to said central portion, said flange being constituted by the folded marginal portion of said blank and the peripheral edge of said blank extending into said groove.

6. An article of the class described formed from a blank comprising fibrous materials, said article including a central portion, a multi-ply flange, a portion constituting a groove and joining said 65 flange to said central portion, said flange being constituted by the folded marginal portion of said blank and the peripheral edge of said blank extending into said groove; and an adhesive interposed between and joining the plies of said flange.

7. A container closure formed from a blank 70 comprising fibrous materials, said closure including a central portion, a multi-ply flange, and a portion constituting a groove and joining said central portion and said flange, the latter being constituted by the folded marginal portion of 75

- said blank and the peripheral edge of said blank extending into said groove, said flange having deformations therein adapted to coact with means on a container for securing said closure thereto.
5. 8. A container closure formed from a blank comprising fibrous material, said closure including a central portion having an annular rib adapted to engage the edge of the container surrounding an opening in the latter, a multi-ply flange, and a portion constituting a groove joining said flange and said central portion, said multi-ply flange being constituted by the folded marginal portion of said blank and the peripheral edge of said blank extending into said groove.
10. 9. A container closure formed from a blank comprising fibrous material, said closure including a central portion having an annular rib adapted to engage the edge of the container surrounding an opening in the latter, a multi-ply flange, a portion constituting a groove joining said flange and said central portion, said multi-ply flange being constituted by the folded marginal portion of said blank and the peripheral edge of said blank extending into said groove, and a thermoplastic adhesive interposed between and joining the plies of said flange.
15. 10. The process of making a container closure comprising a fibrous material which consists in folding the marginal portion of a blank into flanged relation with the central portion thereof, folding a part of said marginal portion over on the other part thereof to form a double-ply flange, and simultaneously pressing and heating the plies of said flange to activate a thermoplastic adhesive thereon and thereby adhesively join said plies to each other.
20. 11. The process of making a container closure or the like comprising a fibrous material which consists in simultaneously folding the marginal portion of a blank into flanged relation with the central portion thereof and forming a groove between said marginal and central portions, and folding said marginal portion to form a multi-ply flange with the edge of said marginal portion extending into said groove.
25. 12. The process of making a container closure or the like comprising a fibrous material which consists in simultaneously folding the marginal portion of a blank into flanged relation with the central portion thereof and forming a groove between said marginal and central portions, folding said marginal portion to form a multi-ply flange with the edge of said marginal portion extending into said groove, and deforming said

multi-ply flange by the application of pressure to render the same cooperable with means on the container for securing said closure thereto.

13. The process of making an article of the class described comprising a fibrous material 5 which consists in simultaneously bending the marginal portion of a blank into flanged relation with the central portion thereof and forming a groove between said marginal and central portions, folding said marginal portion to form 10 a multi-ply flange with the edge of said marginal portion extending into said groove, and simultaneously pressing and heating the plies of said flange to activate a thermoplastic adhesive thereon and thereby adhesively join said plies. 15

14. The process of making a container closure comprising a fibrous material which consists in forming an annular rib in the central portion of a blank, drawing the marginal portion of said blank into flanged relation with said central portion and simultaneously forming a groove between said marginal portion and said rib, and folding said marginal portion to form a multi-ply flange with the edge of said marginal portion extending into said groove. 20

15. The process of making a container closure comprising a fibrous material which consists in forming a flat, annular rib having a substantial radial width in the central portion of a blank, drawing the marginal portion of said blank into 30 flanged relation with said central portion and simultaneously forming a groove between said marginal portion and said rib, folding said marginal portion to form a multi-ply flange with the edge of said marginal portion extending into said 35 groove, and deforming said flange by the application of pressure to render the same cooperable with means on the container for securing said closure thereto.

16. The process of making a container closure 40 comprising a fibrous material which consists in forming an annular rib in the central portion of a blank, drawing the marginal portion of said blank into flanged relation with said central portion and simultaneously forming a groove between said marginal portion and said rib, folding said marginal portion to form a multi-ply flange with the edge of said marginal portion extending into said 45 groove, and simultaneously pressing and heating the plies of said flange to activate a thermoplastic adhesive thereon and thereby adhesively join said plies. 50
